UNITED STATES PATENT OFFICE

LEWIS B. WINTON, OF GREENWICH, CONNECTICUT, ASSIGNOR, BY MESNE ASSIGNMENTS, TO AMERICAN SEALCONE CORPORATION, OF NEW YORK, N. Y., A CORPORATION OF NEW YORK

RECEPTACLE HEADING APPARATUS

Application filed September 24, 1930. Serial No. 483,982.

This invention relates to a lubricating system particularly adapted to be used in connection with receptacle heading apparatus and of such construction and arrangement as 5 to be readily applied to existing heading apparatus.

The receptacle heading apparatus to which the present invention is adapted to be applied, is embodied in a machine for making 10 paper receptacles, as disclosed in Letters Patent #1,628,074, issued May 10, 1927, and by which a sheet of paper is formed into a conical tubular body into one end of which a flanged paper disk is inserted with the 15 disk flange extending outwardly in contiguous relation to the wall of the body and secured in the body by rolling together the disk flange and contiguous portion of the body by spinning apparatus, there being two of 20 such apparatus of substantially the same design and structure to primarily break down and then roll the disk flange and body into securing and intimate relation. Each apparatus comprises a revoluble spinning head 25 adapted to be reciprocated axially toward and away from the receptacle body and inserted bottom disk and carrying rotatable rollers having a V-shaped recess about the periphery to engage the edges of the disk 30 flange and contiguous portion of the receptacle body upon the reciprocation of the head toward the positioned receptacle, which engagement will cause the rollers to rotate at high speed due to the rapid rotation of the 35 head. The rollers are rotatably mounted on studs spaced about and projecting from the periphery of the head with a close fit to assure an even rolling by maintaining the roller recesses in alinement. Due to this 40 close fit and the speed at which the rollers are rotated heat of a high temperature is created causing the material of the rollers and studs to expand and freeze one to the other preventing rotation of the rollers and 45 resulting in the rollers sliding about the disk flange and receptacle body, not only causing wear of the rollers but also scorching of the material of the receptacle body and bottom and rendering the receptacle useless.

50 It is the principal object of the invention

to prevent the frequent replacement of the rollers and the rendering of the receptacles useless caused by this faulty structure of the present heading apparatus by providing 55 automatic lubricating means for the bearing surfaces between the rollers and supporting studs which is simple in structure and inexpensive to apply to new or existing apparatus.

The embodiment of the invention comprises a reservoir for oil fixedly mounted 60 relative to the reciprocating head and adapted to feed oil by gravity to an oil carrying well arranged in the head in communication with the oil reservoir in all positions of 65 said head, the oil in the oil carrying well being delivered to the bearing surfaces between the rollers and studs by ducts arranged in the studs in communication with said well and opening to the bearing surfaces 70 of the studs.

In the drawings accompanying and forming a part of this application, Figure 1 is a plan view showing the heading apparatus having the invention embodied therein and 75 a part of receptacle holding mechanism of the receptacle forming machine with the remaining part of the machine broken away.

Figure 2 is an elevational view showing the embodiment of the invention relative to 80 a spinning head.

Figure 3 is a view looking at the right of Figure 2, with the spinning head removed.

Figure 4 is an end view of the spinning 85 head showing the oil carrying well and reservoir connection therewith in dotted lines.

Figure 5 is a sectional view of the spinning head taken on line 5—5 of Figure 4, looking 90 in the direction of the arrows.

Figure 6 is a sectional view of a roller supporting stud showing the arrangement of oil ducts therein.

Figure 7 is a view of means for connecting the oil reservoir to the oil carrying well in 95 the spinning head.

Figure 8 is a view looking at the right of Figure 7 showing a part of the oil well portion of a spinning head in relation thereto, and 100

Figure 9 is a view looking at the top of Figure 7.

To clearly illustrate the invention in the accompanying drawings, an embodiment of the invention is shown in Figure 1 in connection with a general arrangement of a pair of heading apparatus of a receptacle making machine relative to a series of receptacle body holders 10 each holder comprising a pair of semi-circular mating sections tapering from one end to the other connected at one marginal edge portion and mounted on a revolute carrier disk 11 supported by a table 12, the holders 10 being successively positioned, as at *a*, by the intermittent movement of the disk relative to a mandrel (not shown) about which a blank is wrapped to form a conical body, the formed body being delivered from the mandrel into a holder stationed relative to the mandrel by the carrier disk with the end portion of the receptacle body of largest diameter extending from the holder, as at *b*, the sections of the holders being separated by means carried by the disk 11 to facilitate inserting the formed receptacle body therein. Upon the next successive movements of the disk 11 the holders are positioned at station *b*, and then to station *c* relative to means (not shown) to form a flanged disk and position the same into the extending end of the receptacle with the flange extending outward from the disk in contiguous relation to the wall of the extended receptacle end. The holders with a flanged disk engaged in a body therein are then moved to position *d* relative to the primary or first heading apparatus, as shown in *A* in Figure 1, where the disk flange and receptacle body are primarily rolled together or interfolded. Upon the next movement of the disk 11 the holders are positioned, as at *e*, relative to the second or final heading apparatus, as indicated at *B*, which is of the same structure as the primary heading apparatus. The holders are then successively moved to positions *f* and *g* and the receptacles delivered from the holders at the latter station.

Each of heading apparatus comprises a spinning head (indicated in a general way at *H* in Figure 1,) rotatably mounted on a standard *S* fixed upon the table 12 in alignment with the holders at stations *d* and *e*. The head is fixed to a shaft 14 rotatably and slidably mounted in a bearing at the top of the standard and retained by a cap 15, arranged as shown in Figure 3. The spinning head is rotated by a motor *M* the drive shaft 16 of which is coupled to the head carrying shaft 14 to permit of sliding movement of the shaft 14 toward and away from the receptacle holders by a perforated collar 17 fixed to the shaft 16, pins 18 extended from an annularly recessed collar 19 fixed to the end of shaft 14, slidably engaging in the perforations in collar 17. The spinning heads *H* are

actuated toward the receptacle holders during the periods of rest of the holder disk 11, by levers 20 arranged with a bifurcated end 21, Figure 3, the legs of which engage at opposite sides of the collars 19 with rollers 21' mounted on pins fixed in the bifurcation legs engaging in the collar recess. The lever 20 for head *B* is fixed at the opposite end on a shaft 25 carried by the standard *S*, and is reciprocated from the drive shaft 22 of the receptacle making machine through a cam wheel 23 fixed to shaft 22 and a cam following roller 24 in the cam groove of wheel 23 carried by an arm fixed to the shaft 25. The actuating lever 20 for the heading apparatus *A* is connected with shaft 25 to be reciprocated in synchronism with the lever 20 of heading apparatus *B* by an arm 26 fixed to shaft 25 having pivotal connection 27, with an arm 28 fixed on a spindle 29 rotatably mounted in the standard *S* of the heading apparatus *A* and to which the lever 20 of said heading apparatus is fixed, rocking of shaft 25 to move the spinning heads toward the positioned receptacle holders will rock the pivotal connection 27 of the arms 26, 28 in a downward direction thereby moving the bifurcated end of the lever 20 toward the standard *S*. The motor of the heading apparatus *A* is supported from the table 12 in spaced relation there-to to permit the mounting of the rock shaft 25 on the table by blocks at the ends of the base of the motor, as indicated in dotted lines at 30 in Figure 1. The spinning heads *H* are yieldingly urged toward the holders by a spring 80 fixed to the bifurcated ends 21 of the levers 20 and the standards *S*, as shown in Figure 2. Each of the spinning devices comprise a head 31 fixed to reduced ends of shafts 14 in abutting relation to an annular shoulder 32 by a perforated disk 33 engaging in an enlarged recess 34 in the outer face of the head and a screw 35 passed through the disk perforation and threaded into the shaft. Rollers 36 having a V-recess 37 about the peripheral edge for spinning engagement with the edges of the disk flange and receptacle body are rotatably mounted in diametrical opposite pairs on the side of the head by studs 38 having a reduced end portion for engagement and mounting in bores 39 extended into the head 31 radially of the shaft 14, as shown in Figure 4. The studs are secured and held against rotation in the bores by screws 40 threaded in the head 31 engaging in a recess 41 in the reduced end of the studs, as shown in Figure 5. The rollers are retained on the studs by providing the studs with heads 42 at the free ends with interposed ball bearings 57. The rollers carrying studs are retained in position in the head bores 39 by a ring 43 extended about the head and fixed thereto by screws 44 threaded into arms 45 extended from the head 31 in interposed relation to the rollers 130

with screws 46 threaded through the ring engaging the stud heads 42. To retain the bottom of the receptacle in alignment with the spinning rollers 36 during the spinning operation an annular plate 49 is mounted on the outer face of the head 31 by the screws 40, the surface of the plate being recessed at the juncture of the face and periphery of the plate, as at 50, to engage the inner edge 16 of the rolled portion of the closure disk and receptacle body and maintain the receptacle in alignment with the heading rollers.

The bearing portions of the studs 38 upon which the rollers 36 are rotatably mounted 15 are of a diameter relative to the bores of the rollers that the rollers have no lateral movement when engaged with a closed receptacle end to assure maintaining the rolling recesses 37 of the rollers 36 in alignment with each 20 other. By this method of mounting the rollers on the studs, heat of a high temperature is developed due to the speed of rotation of the roller carrying head necessary to properly crimp and roll together the material of 25 the disk flange and the receptacle body, and to also produce a large number of receptacles during a given period of time. The heat thus developed causes expansion of the material of the rollers and supporting studs 30 which will cause the material to seize and prevent the rollers from rotating, thereby effecting a rolling together of the closure disk flange and the receptacle body by only a portion of the roller recesses 37 and a calendering 35 action which will cause undue wear and render the rollers useless. This will also develop sufficient heat to scorch and burn the material of the closure disk and receptacle body rendering the receptacle useless.

40 To overcome the overheating of the bearings of the rollers it was necessary to stop the operation of the machine after short periods to oil said bearings by hand thereby reducing the number of receptacles produced and capacity of the machine considerably. To overcome this disadvantage of overheated bearings without stopping the operation of the machine means have been provided to automatically lubricate the 45 bearings of the rollers and is in the nature of a gravity and force feed system to provide a film of oil continuously between the bearing surfaces of the studs 38 and rollers 36. For this purpose the studs are 50 arranged with a bore or duct 51 extending diagonally and longitudinally through the studs, said duct having an opening at one end adjacent the head 42 and at the other end communicating with a recess 52 in 55 the portion of the studs engaging the bores 39 of the roller head 31 and opposite the recess 41 in the studs. A bore or duct 53 is extended laterally from and communicates with the duct 51 and opens to the 60 bearing surface of the stud at a point inter-

mediate the ends of the roller supporting portion thereof. The oil is supplied to the ducts from an oil carrying well in the spinning head 31 in the form of an annular recess 54 arranged in the inner face of the 70 head with the walls thereof extending in an oblique direction toward the sides of the head whereby a quantity of oil by the action of centrifugal force through the rotation of the head is retained in the recess 75 for delivery through perforations 55 into the stud recesses 52 and the ducts 51 to the bearing surfaces between the hub portions 47 of the rollers and the adjacent sides of the head 31, and then into the oil ducts 53 to 80 lubricate the bearing surfaces between the studs and rollers. The oil is also delivered from the ducts 51 into a chamber formed by a recess 56 in the outer side of the rollers 36 and the heads 42 of the studs 38 for the 85 purpose of lubricating bearings 57 carried by a cage 58 mounted on the studs with the balls in the chamber 56 interposed between the rollers and stud heads.

The oil is retained in the recess 54 for 90 the entire circumference thereof through the action of centrifugal force induced by the rotation of the head and to prevent the oil from leaving the recess the inner wall of the recess is of less height than the 95 outer wall, the outer wall being in the form of an annular flange 59 in spaced relation with a hub portion 60 of the head 31 which forms the inner wall, the space between the flange 59 and hub 60 constituting the recess 100 54, as shown in Figure 5.

The oil is retained in the oil well in the head at a predetermined level and in sufficient quantity to assure lubricating all of the friction surfaces by an intermittent supply of oil from an oil reservoir or container 61, Figures 2 and 3 having a filler opening with a pivoted closure 62 and a valved controlled outlet through a reduced tubular portion, as at 63, the valve being adapted to be actuated by a lever 64 pivotally mounted at the top of the reservoir, or the valve may be of the automatic type permitting an intermittent flow of liquid. The reservoir is fixed on the standard S by securing the reduced tubular portion 63 in a collar 65 at the top of a housing member 66 fixed relative to the bearing cap 15 on the standard S by a pair of perforated ears 67 extending laterally from and integral with aligned sleeves 68 fixed in and extending from the end walls of the housing, as shown in Figures 7 to 9, inclusive, the ears being mounted on the standard S by the bolts which secure the cap 15 to the 115 standard, as shown in Figure 3.

To connect the oil reservoir to the oil well 54 in all positions of the spinning heads H relative to the closed receptacle end oil connecting means is provided to reciprocate in 120 125

5 synchronism with the reciprocatory movement of the spinning head carrying shaft 14, and comprises a rectangular body 69 having an oil receiving pocket 73 and slidably mounted within the housing member 66 in alignment with and below the reservoir outlet 63 by rods 70, 71 fixed in and extended from opposite sides of the body slidably engaging in the housing sleeves 68 with the free ends 10 of the rods projecting beyond the sleeves. The rod 70 is pivotally connected at the free end thereof to the upper end 21 of the lever 20, as at 72, whereby the reciprocatory movement of the shaft 14 is imparted to the body 15 69. The oil delivered from the reservoir 61 is received in the pocket 73 in the body 69 which is of such size to receive the oil from the reservoir in all the reciprocatory adjusted positions of the oil receiving body, and the 20 oil is fed from the pocket 73 to the oil well 54 by gravity through a bore or duct 74 leading through and from the body 69 in communication with a bore extended through the supporting rod 71, the projected end of rod 71 25 being arranged with a spout or nozzle 75 in communication with the bore of rod 71 and extended laterally of the rod in juxtaposed relation to the standard S at the rear of spinning head 31 with the outlet end thereof bent 30 downward to extend into the lowermost portion of the oil well adjacent the flange 59, as shown in dotted lines in Figure 5, this position of the nozzle relative to the oil well being maintained due to the reciprocatory 35 mounting and positive connection of the oil receiving pocket 73 with the shaft 14. The bore 74, the bore in the rod 71 and nozzle form a conduit reciprocatory in synchronism with the movement of the head through 40 which oil is automatically delivered by gravity to the oil well from a source of supply. To facilitate the assembling and cleaning of the oil receiving body 69 the exposed face of the housing 66 is open, as shown in Figures 45 2 and 7, and to prevent oil from splashing from the housing during the operation of the apparatus, the opening is enclosed by a cover plate 76 releasably secured to the housing by screws 77 passed through perforations at the 50 corners of the plate and threaded into bosses 78 at the corners of the opening to the housing.

While I have described and illustrated one embodiment of the invention it will be obvious that various modifications may be made in construction and arrangement of parts without departing from the scope of the invention and that portions of the invention may be used without others and come 55 within the scope of the invention.

Having thus described my invention, I claim:

1. In receptacle heading apparatus, a rotatable shaft, a member fixed to the shaft arranged with an annular oil receiving well,

and heading rollers rotatably mounted on and circumferentially disposed about said member, said member having ducts therethrough leading from the well to the bearing surfaces of the rollers for the delivery of oil from the oil well to said bearing surfaces through the action of centrifugal force induced by the rotation of the shaft.

2. In receptacle heading apparatus, a rotatable shaft, a head fixed to the shaft having an annular oil well arranged concentrically of the shaft, and heading rollers mounted on the head to rotate on axes extending radially of the shaft, said head having oil ducts in communication with and leading from the oil well to the bearing surfaces of the rollers to deliver oil from the well and lubricate said surfaces by the action of centrifugal force induced by the rotation of the shaft.

3. In receptacle heading apparatus, a rotatable shaft, a head fixed to the shaft arranged with an annular oil well concentrically of the shaft, studs fixed in and extending radially from the head and having oil ducts in communication with the oil well and opening to the outer surfaces of the extended portion of the studs, and heading rollers rotatably mounted on the studs relative to the oil duct openings for the purpose specified.

4. Receptacle heading apparatus as claimed in claim 3, wherein one of said oil ducts extends diagonally through the stud having one end in communication with the oil well and the other end opening adjacent to the outer side of the rollers.

5. Receptacle heading apparatus as claimed in claim 3, wherein one of said oil ducts extends diagonally through the stud with one end in communication with the oil well, and the other duct leading from the first duct to the outer surfaces of the stud.

6. In receptacle heading apparatus, a rotatable shaft, a head fixed to the shaft arranged with an annular oil well extending concentrically of the shaft, studs fixed in and extending radially from the head having oil ducts in communication with the oil well and opening to the outer surfaces of the extended portion of the studs, and heading rollers rotatably mounted on the studs relative to the oil duct openings and having a recess therein in communication with the oil well through one of the ducts.

7. In receptacle heading apparatus, a shaft mounted to rotate and have longitudinal reciprocatory movement, a head fixed to the shaft arranged with an oil carrying well, heading rollers rotatably mounted on and circumferentially disposed about the head, said head having oil ducts in communication with the oil well and opening to the bearing surfaces of the rollers, a fixed oil reservoir, and means adapted to connect and maintain the reservoir in communication with the oil

well in the head in all the longitudinal adjusted positions of the shaft.

8. In receptacle heading apparatus, a shaft mounted to rotate and have longitudinal reciprocal movement, a head fixed to the shaft arranged with an oil well, heading rollers rotatably mounted on and circumferentially disposed about the head, the head having oil ducts in communication with the oil well and opening to the bearing surfaces of the rollers, a fixed oil reservoir, and means reciprocatory in synchronism with the reciprocatory movement of the shaft adapted to receive oil from the reservoir in all positions thereof and deliver the same to the oil well in the roller carrying head.

9. Receptacle heading apparatus as claimed in claim 8, wherein the oil is delivered from the oil receiving means to the oil well in the roller carrying head through a duct in the mounting of said means, and a spout in communication with said duct and extended into the oil well of the head.

10. Receptacle heading apparatus as claimed in claim 8, wherein the reservoir is arranged with a drip controlled outlet, and means to receive oil from the reservoir and deliver it to the oil well in the head, comprises a block slidably mounted below said outlet having a pocket therein to receive the oil from the reservoir.

11. In receptacle heading apparatus, a rotatable shaft, a head fixed to the shaft arranged with an annular oil well concentrically of the shaft, studs fixed in and extending from the head radially of the shaft arranged with an annular head at the outer ends and having oil ducts in communication with the oil well and opening to the outer surfaces of the extended portion of the studs, and heading rollers rotatably mounted on the studs having a recess in the outer side to form a chamber with the annular head of the studs, and one of the stud oil ducts opening to said chamber.

12. In receptacle heading apparatus, a standard, a shaft mounted in the standard to rotate and having sliding movement, a head fixed to the shaft and arranged with an oil well, heading rollers rotatably mounted on the head circumferentially spaced about the shaft and having oil ducts in communication with the oil well and opening to the bearing surfaces of the rollers, an oil reservoir fixedly mounted on the standard, an oil receiving member mounted on the standard relative to the outlet of the oil reservoir and connected to the shaft to participate in the sliding movement thereof, and a conduit carried by said oil receiving member and extended to the oil well in the head.

13. In receptacle heading apparatus, a standard, a driven shaft mounted in the standard to rotate and have sliding movement, a head fixed to the shaft having an annular oil

well, heading rollers rotatably mounted on the head and circumferentially spaced about the shaft and having oil ducts in communication with the oil well and opening to the bearing surfaces of the rollers, means to reciprocate the shaft in the direction of the axis, an oil reservoir fixedly mounted on the standard having an outlet from the bottom thereof, an oil receiving member mounted on the standard below the reservoir outlet to have movement in the direction of the axis of the shaft and having a connection with the shaft reciprocating means to be actuated in synchronism with the movement of the shaft, and a conduit carried by the oil receiving member and extended to the oil well in the roller carrying head for the purpose specified.

14. Receptacle heading apparatus as claimed in claim 13, wherein the oil receiving member comprises a recessed body, and rods fixed to and extended from the body slidably mounted in the standard, one of said rods being connected to the shaft actuating means, and the other rod arranged with a bore in communication with the recess in the body and the conduit.

Signed at the city of New York, in the county of New York and State of New York, this 16th day of September, 1930.
